Des. 242,390
Patented Nov. 16, 1976

242,390

BACK MASSAGER

Clifford E. Grube, Niles, Ill., assignor to
Associated Mills, Inc.

Filed Sept. 2, 1975, Ser. No. 609,502

Term of patent 14 years

Int. Cl. D6—09; D28—03

U.S. Cl. D83—1 S

FIG. 1

FIG. 2

FIG. 3

FIG. 4

FIG. 6

FIG. 5

FIG. 7

FIG. 1 is a perspective view of a back massager showing my new design;

FIG. 2 is an elevational view of one side thereof;

FIG. 3 is an end elevation as seen from the left of FIG. 2;

FIG. 4 is a top plan view thereof;

FIG. 5 is an end elevation as seen from the right of FIG. 2;

FIG. 6 is an elevational view of the other side thereof; and

FIG. 7 is a bottom plan view thereof.

I claim:

The ornamental design for a back massager, substantially as shown and described.
